US00D995432S

(12) **United States Design Patent** (10) **Patent No.:** **US D995,432 S**
(45) **Date of Patent:** **** Aug. 15, 2023**

(54) **CORE COMPONENT**

(71) Applicant: **SUMIDA CORPORATION**, Tokyo (JP)

(72) Inventor: **Hitoshi Moriya**, Natori (JP)

(73) Assignee: **SUMIDA CORPORATION**

(**) Term: **15 Years**

(21) Appl. No.: **29/781,310**

(22) Filed: **Apr. 29, 2021**

Related U.S. Application Data

(62) Division of application No. 29/698,492, filed on Jul. 17, 2019, now Pat. No. Des. 920,912.

(30) **Foreign Application Priority Data**

(57) **CLAIM**

The ornamental design for a core component, as shown and described.

DESCRIPTION

FIG. 1 is a front elevation view of a core component, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, right side perspective view thereof; and,

FIG. 8 is a bottom, front, right side perspective view thereof. The broken lines in the drawings show environment only and form no part of the claimed design.

1 Claim, 8 Drawing Sheets
